CLAIM

The ornamental design for an endoscope handle, as shown and described.

DESCRIPTION

FIG. 1 is a front perspective view of an endoscope handle showing my new design;

FIG. 2 is a left side view thereof;

FIG. 3 is a right side view thereof;

FIG. 4 is a rear view thereof;

FIG. 5 is a front view thereof;

FIG. 6 is a top view thereof; and,

FIG. 7 is a bottom view thereof.

The dash-dot broken lines shown on the endoscope handle disclose boundaries only and form no part of the claimed design.

The dashed broken lines shown on the endoscope handle illustrate environment that forms no part of the claimed design.

1 Claim, 7 Drawing Sheets
